(57) **CLAIM**

The ornamental design for a camera, as shown and described.

DESCRIPTION

FIG. 1 is a perspective view of a camera showing our new design;

FIG. 2 is another perspective view thereof;

FIG. 3 is a front view thereof;

FIG. 4 is a rear view thereof;

FIG. 5 is a left view thereof;

FIG. 6 is a right view thereof;

FIG. 7 is a top view thereof;

FIG. 8 is a bottom view thereof; and,

FIG. 9 is an operational bottom view thereof, showing a lens rotated to a bottom of the camera.

The portions of the Figures shown in broken lines are shown for illustrative purposes only and form no part of the claimed design.

1 Claim, 9 Drawing Sheets
